UNITED STATES PATENT OFFICE

134,567

DESIGN FOR A BRACELET LINK

Louis G. Meyers, New York, N. Y.

Application October 1, 1942, Serial No. 108,382

Term of patent 7 years

To all whom it may concern:

Be it known that I, Louis G. Meyers, a citizen of the United States, residing at New York city, in the county of New York and State of New York, have invented a new, original, and ornamental Design for a Bracelet Link, of which the following is a specification, reference being had to the accompanying drawing, forming part thereof.

In the drawing:

Fig. 1 is a top plan view of a bracelet link, showing my new design; and

Fig. 2 is a front elevation of Fig. 1.

I claim:

The ornamental design for a bracelet link, substantially as shown.

LOUIS G. MEYERS.
